DESIGN FOR A SUITCASE OR THE LIKE

Jack Krohn, Irving Steinlauf, and Samuel Schwartz, New York, N. Y.

Application January 7, 1942, Serial No. 105,042

Term of patent 7 years

To all whom it may concern:

Be it known that we, Jack Krohn, Irving Steinlauf, and Samuel Schwartz, all citizens of the United States and all residents of New York city, in the county of New York and State of New York, have invented a new, original, and ornamental Design for a Suitcase or the like, of which the following is a specification, reference being had to the accompanying drawing, forming a part thereof.

In the drawing:

Fig. 1 is a perspective view of a suitcase or the like, showing our new design.

Fig. 2 is a top plan view of the same.

Fig. 3 is a bottom plan view of the same.

We claim:

The ornamental design for a suitcase or the like, as shown.

JACK KROHN.
IRVING STEINLAUF.
SAMUEL SCHWARTZ.
